UNITED STATES PATENT OFFICE.

BERT CARLISLE, OF SANTA ANA, CALIFORNIA.

AUTOMATIC TRAIN-STOP.

1,307,807.

Specification of Letters Patent. Patented June 24, 1919.

Application filed February 21, 1918. Serial No. 218,464.

To all whom it may concern:

Be it known that I, BERT CARLISLE, a citizen of the United States, residing at Santa Ana, in the county of Orange and 5 State of California, have invented new and useful Improvements in Automatic Train-Stops, of which the following is a specification.

My object is to make a device which may 10 be applied to a steam locomotive drawing a train supplied with air brakes and set so that when a train goes a certain predetermined distance the apparatus will blow the whistle, close the throttle, and set the air 15 brakes.

Figure 1 is a diagrammatic plan illustrating the application of my automatic train stop to a locomotive.

Fig. 2 is a detail, partly in elevation and 20 partly in section, of the gage, as seen looking in the direction indicated by the arrows 2 in Figs. 1 and 3.

Fig. 3 is a sectional detail on the line 3—3 of Fig. 2.

25 Fig. 4 is a fragmentary plan of the locomotive throttle lever and showing the connection to the automatic train stop.

Fig. 5 is a cross-section of the forward 30 tender axle and showing the connection for operating the automatic train stop.

Fig. 6 is a sectional detail on the line 6—6 of Fig. 5.

Referring to Figs. 1, 2 and 3, the pipe 1 leads from the compressed air tank 2 to a 35 stop cock 3, and an operating lever 4 is fixed upon the stem 5 of the stop cock and a stop arm 6 extends from the operating lever 4 and engages a stop lug 7, so that when the lever 4 is thrown over to bring 40 the stop arm 6 into engagement with the stop lug 7 the valve is closed.

The gage base 8 is mounted upon the shelf 9 of the tender 10 adjacent to the stop cock 3. A gear case 11 extends upwardly from 45 the base 8 and a gage front 12 is mounted upon the gear case by screws 13. Shafts 14 and 15 are mounted horizontally in the gear case parallel with each other. A worm gear 16 is loosely mounted upon the shaft 14 and carries a pinion 17 meshing with a large gear 18 loosely mounted upon the shaft 15, said gear 18 carrying a pinion 19 meshing with a large gear 20 loosely mounted upon the shaft 14 and carrying a pinion 21 55 meshing with a large gear 22 keyed upon the shaft 15. A gear worm 23 is mounted in

the case in mesh with the worm gear 16. A disk 24 is fixed upon the shaft 15 in front of the gage front 12 and has an annular flange 25 extending from its edge forwardly. The 60 indicator arm 26 is loosely mounted upon a journal 27 extending from the forward end of the shaft 15, said arm 26 having a return bend 28 forming a slot 29 in which the flange 25 normally moves freely. A clamping 65 screw 30 is inserted through the return bend 28 so that by manipulating the clamping screw 30 the return bend 28 is pinched to clamp the arm 26 to the flange 25. A pointer 31 extends from the outer end of the return 70 bend 28 to the graduations 32 upon the gage front 12. An arm 33 extends from the return bend 28 at approximately right angles to the arm 26 and in position to engage under the operating lever 4 and move the 75 operating lever 4 from the position shown in full lines, that is the closed position of the stop cock, to the position shown in dotted lines that is the open position of the stop cock. In laying out the graduations 32 upon the gage front 12, the circle is divided into one hundred parts and the 80 graduations are intended to count the parts from one to one hundred.

Referring to Figs. 5 and 6, a spur gear 34 85 is made in two pieces and mounted upon the tender axle 35, the two pieces being clamped together by bolts 36 and there being a key 37 to hold the gear from rotating upon the axle. Arms 38 and 39 are journaled 90 upon the hub of the gear 34 and a second spur gear 40 is mounted between the arms 38 and 39 and has a spindle 41 extending through bearings 42 and 43 in the arms. A link 45 connects the outer ends of the arms 95 38 and 39 to a bracket 46 secured to the bottom of the tender. A flexible shaft 47 connects one end of the spindle 41 to the gear worm 23.

If the size of the tender wheel 48 is such 100 that six hundred and sixty revolutions of the wheel will travel a mile and there are sixty-six teeth upon the worm gear 16 and the gear worm 23 is a single thread worm moving the gear 16 one tooth to each revolution of the worm, then six hundred and sixty revolutions of the tender wheel 48 will rotate the gear 16 ten revolutions. The ratio between the pinion 17 and the gear 18 is one to ten, the ratio between the pinion 19 and the gear 20 is one to ten, and the 105 ratio between the pinion 21 and the gear 22 is one to ten.

22 is one to 10. Then when the tender wheel 48 has traveled one mile, the pointer 31 will move one one-hundredth of a revolution, or from one graduation to the next. 5 If the train is to be started to run fifteen miles and stop, the set screw 30 will be loosened, the arm 26 swung to bring the pointer to the graduation "15", and the set-screw manipulated to tighten the arm 26 upon the flange 25. Then when the train has gone fifteen miles the arm 33 will have engaged the lever 4 and thrown it over to open the air line through the pipe 1.

The pipe 49 leading from the stop cock 3 is connected to the air cylinder 50. The piston 51 in the cylinder 50 operates a piston rod 52 and a cord 53 connected to the outer end of the piston rod 52 passes through a bearing 54 in the end of the locomotive throttle lever 55 and is attached to the latch operating lever 56, and a cord 57 connects the end of the piston rod 52 to the whistle operating mechanism, so that when the stop cock 3 is opened the piston 51 will be moved to blow the whistle, pull the latch lever 56, release the throttle lever 55, swing the throttle lever over to throttle the locomotive, and shut off the power. When the piston 51 reaches the bottom of the cylinder 50 a by-pass 58 is opened to the air cylinder 59 behind the piston 60 and the piston 60 has a piston rod 61 connected by a cord 62 to the lever 63, said lever operating the air brake system, so that when the piston 60 is moved 35 by the air pressure passing through the port 58 the lever 63 is operated to set the brakes and stop the train.

The lower end of the flexible shaft 47 is connected to a bevel gear 64 and this bevel gear 64 meshes with a bevel gear 65 fixed upon the spindle 41 so as to make a right angled joint between the shaft and the spindle.

A blow-off valve 66 is connected to the bottom of the cylinder 50 to let air out of the cylinder when it is desired to restore the mechanism to normal position and start the train. Before opening the blow-off valve 66 the operating lever 4 must be moved back 50 to closed position to stop the air from flowing through the pipe 49.

Thus I have produced an automatic train stop which may be set so that the train will run a certain distance and the operation of the stop mechanism will first blow the whistle and throttle the locomotive, and continued operation will set the air brakes and stop the train.

Various changes may be made in the details of construction without departing from the spirit of my invention as claimed.

I claim:

1. An automatic train stop construction comprising the combination with a pipe leading from the compressed air tank of the air brake system, of a stop cock incorporated into the pipe, an operating lever fixed upon the stem of the stop cock, a gage base mounted adjacent to the stop cock, a gear case extending upwardly from the gage base, a train of gearing mounted in the gear case and having a shaft extending forwardly, a gage front mounted around the shaft, an indicator arm loosely mounted upon the shaft, a disk fixed upon the shaft in front of the gage front and having an annular flange extending from its edge, a return bend upon the end of the indicator arm forming a slot in which the flange moves, a clamping screw inserted through the return bend to clamp the arm to the flange, a pointer extending from the outer end of the return bend to the graduations upon the gage front, an arm extending from the return bend at right angles and adapted to engage under the operating lever to move the stop cock from its closed position to its open position, and means for operating the train of gearing from a car wheel axle.

2. An automatic train stop construction comprising the combination with a pipe leading from the compressed air tank of the air brake system, of a stop cock incorporated into the pipe, an operating lever fixed upon the stem of the stop cock, a gage base mounted adjacent to the stop cock, a gear case extending upwardly from the gage base, a train of gearing mounted in the gear case and having a shaft extending forwardly, a gage front mounted around the shaft, an indicator arm loosely mounted upon the shaft, a disk fixed upon the shaft in front of the gage front and having an annular flange extending from its edge, a return bend upon the end of the indicator arm forming a slot in which the flange moves, a clamping screw inserted through the return bend to clamp the arm to the flange, a pointer extending from the outer end of the return bend to the graduations upon the gage front, an arm extending from the return bend at right angles and adapted to engage under the operating lever to move the stop cock from its closed position to its open position, and means whereby the opening of the stop cock operates the throttle to shut off the power and operates the air brake system to set the brakes and stop the train.

In testimony whereof I have signed my name to this specification.

BERT CARLISLE.
